CLAIM

The ornamental design for an orbital sander, as shown.

DESCRIPTION

FIG. 1 is a top front right-side perspective view of an orbital sander showing our new design with the handle separated for ease of illustration;

FIG. 2 is a top plan view;

FIG. 3 is a bottom plan view;

FIG. 4 is a left elevational view;

FIG. 5 is a right elevational view thereof;

FIG. 6 is a front elevational view; and,

FIG. 7 is a rear elevational view thereof.
